2 Claims. (Cl. 197—133)

This invention has reference to apparatus for feeding continuous webs of stationery to a typewriter or the like machine.

In typewriters it is known to have mechanism which rotates the platen, for example, a single space, to feed the continuous stationery one line. It is also known to provide typewriter mechanism which will continue to rotate the platen and hence feed the stationery, while a line feed key remains depressed.

In typing continuous stationery webs it is required to type certain data at the top of a form length and then "throw" or long feed the stationery web to a second position whereat further data is typed. The web is then fed to a further position whereat for example, information is typed. When all the information is typed the web is again fed to the first typing position on the succeeding form length.

It is an object of the present invention to provide a continuous stationery web feeding device suitable for attachment to the carriage of a typewriter.

It is another object of the invention to provide a feeding device for a continuous web of stationery with the feeding device being controlled so that the stationery is arrested at predetermined positions on each form length as required.

According to the present invention apparatus for feeding continuous stationery in a typewriter or the like machine comprises pin feed mechanisms for feeding the continuous stationery, means for feeding an endless belt bearing indicia corresponding to predetermined form positions in synchronism with the continuous stationery so that the endless belt is completely fed once each time one or more form lengths of the continuous stationery is fed, electric solenoid means to drive the pin feed mechanism with a step-by-step motion, electric control means for the solenoid means and a sensing device to sense the indicia on the endless belt to actuate the control means.

Continuous stationery feeding apparatus will now be described by way of example and with reference to the accompanying drawings wherein:

FIG. 1 is a front perspective view of an apparatus in accordance with the invention;

FIG. 2 is a perspective view of the driving mechanism with the cover removed;

FIG. 3 is a perspective view of the sensing unit with the door open;

FIG. 4 is a view of an endless band for use in the sensing unit;

FIG. 5 is another view (partly cut away) of the sensing mechanism;

FIG. 6 is a view of a guide for the stationery;

FIG. 7 is a circuit diagram of the electrical control circuit; and

FIG. 8 is a view of a length of continuous stationery.

Referring to FIG. 1 there is shown an apparatus for use with a typewriter platen having the usual platen shaft. A pair of brackets *a* are mounted to engage the platen shaft at each end of the platen. The lower part of each bracket has a slot *b* to engage the platen shaft. A drive shaft *c* and a supporting cross bar *d* is secured between the brackets *a* and a pair of endless belt pin feed tractors *e* is mounted on the cross bar *d* and driven by the drive

2

shaft *c*. These tractors may be as disclosed in the Castleton U.S. Patent 3,073,497 of January 15, 1963 in which each comprises a body *f* mounted on the supporting cross bar *d* with a drive sprocket rotatably keyed on to the drive shaft *c* which in turn is rotatably mounted on the body. The teeth of the sprocket engage in the links of the tractor which links are joined in the form of an endless chain. Each link carries a feed pin *g* which engages in a marginal feed perforation *31* of the continuous stationery *30* (FIG. 8) so that as the drive shaft is rotated the tractor will become operative to feed the stationery.

A casing *h* is mounted on the left hand supporting bracket, and an electric solenoid means *j* (FIG. 2) is secured within this casing *h*. The solenoid means *j* comprises a solenoid whose armature is connected to a plate *k* having ball receiving sockets defined by bottoms *l* on which balls (not shown) housed within the respective sockets are free to move. These balls project from their respective recesses toward the adjacent end of the housing or casing of solenoid *j* so that as the armature is attracted by the solenoid, the resulting axial compressing action on the balls between the casing of the solenoid *j* and the inclined bottoms *l* of their respective sockets imparts rotary movement to the plate *k* and also to the armature connected thereto, as well as to the wheel *m* which is connected to and moves with the armature. The number and disposition of the recesses and balls is such that at least one ball will be urged by gravity to the shallow end of its recess so that at least one such ball will be operatively positioned at all times to cause rotary movement of the armature responsive to axial movement thereof. At the end of its movement, the armature is de-energized through opening of an armature switch *29* connected in the circuit of the solenoid winding. The armature is connected to a dish-shaped rotary toothed wheel *m* which moves axially with the armature when the latter is attracted by the solenoid. At the inception of its axial movement this toothed wheel *m* operatively engages a similar driven toothed wheel *n* from which it is normally 40 disengaged. It should be noted that the arrangement of the teeth on these wheels *m* and *n* is such that between them they constitute a unidirectional drive coupling in which the teeth have abruptly presented faces for operative engagement during rotation in one direction and gradually inclined faces to disengage the two wheels during 45 relative rotation in a reverse direction. The driven toothed wheel *n*, which is rotatable but not axially movable, is driven one step for each energisation of the solenoid armature. The driven toothed wheel is connected to 50 a toothed wheel *o* which cooperates with a spring loaded catch, or in other words a conventional detent which engages in the notches between its teeth (not shown) to ensure a single step movement and through a gear train *p* and *p'* with the drive shaft *c* so that each time the rotary 55 solenoid is energised the drive shaft will be rotated one step.

A pin wheel feed *s* for an endless band tape and a photo-electric sensing mechanism *t* is mounted on the right hand side supporting bracket *a*. This comprises 60 a box *v* in which is mounted a rotatable cylinder with pins *x*. The cylinder is mounted on a shaft *10* which is connected at one end through gearing *11* (FIG. 5) to the drive shaft *c* and is rotatable therewith. The other end of the shaft *10* extends outside the covering box *v* and has a knurled head *12*. The shaft *10* is movable axially against spring pressure so that the last gear of the gearing *11* may be disconnected from the gear train temporarily so that the position of the endless band may be aligned with the continuous stationery when desired. Because there is normally a driving connection between this wheel shaft *10* and the tractors *e* the continuous stationery may be fed rearwardly by rotating

the knurled head 12, for example, if the typist makes an error and wishes to retract the stationery web to make an erasure. As shown in FIGURE 5, the drive to the pin feed mechanism is connected to the platen P of the typewriter by gearing 11, 11A and 11B, in which gear 11B is keyed on the platen shaft.

The pins x on the rotatable cylinder are adapted to engage in apertures 13a arranged centrally of an endless band tape 13 to feed it. A guide 14 maintains the band in alignment with the pins x. A light source 15 comprising an electric light bulb is mounted in the box v. The box has a door 16 which houses on its inner face a transistor element which is responsive to light or in other words a photo-transistor and which is connected up in an electric circuit to be described hereinafter and which constitutes a photo-electric sensing mechanism t. The transistor element t is in line with the light bulb 15. The endless band tape passes between the transistor element t and the light bulb 15 to cut off the light falling on the transistor element. However when an aperture in the endless band passes between the light bulb and the transistor element light will then be allowed to fall on the transistor element to energise it.

The endless band (FIG. 4) comprises an endless belt of paper tape, for example, of a width of one inch with a line of feed perforations running centrally and longitudinally thereof, the perforations are spaced to correspond to the spacing of the pins x on the wheel w. The perforations are engaged by the pins x and by which the belt is driven. The band is arranged to be driven through one complete revolution as the tractors drive the continuous stationery for one form length. If desired the forms may be fed two or more form lengths for each complete feed of the endless band.

A series of control apertures 16a, 16b, 16c are punched in the endless band 13 so as to pass between the transistor element t and the light bulb 15 in the box. These control apertures are arranged so that as the endless band reaches a predetermined position—corresponding to a predetermined position on a form length of continuous stationery 30, the light will pass from the light source through the apertures in the box and through apertures in the endless band to the transistor element t to energise it. For example, the apertures 16a, 16b, 16c in the band 13 may comprise indicia and correspond to two data typing positions 32, 33, and an information typing position 34 on the continuous stationery (FIG. 9) and serve for energising the transistor element t for arresting the continuous stationery at these respective positions.

A tube 17 is arranged between the brackets and a cable runs through this tube to be connected up as will be hereinafter described.

A set of infeed guide plates 18 (FIG. 1) and outfeed guide plates 19 serve to guide the continuous stationery. These guide plates are mounted on adjustable supporting cross bars 20. The outer infeed guide plates (FIG. 6) are adjustably secured to the cross bar 20 by being mounted on a support block 21 on which is pivoted a wedge bar 22. A spring 23 urges the bar 22 against the cross bar 20 to hold the plate in position. When the bar 22 is pulled against the action of the spring 23 the wedge action of the bar 22 is released and the support block and guide plate are free to slide on the bar 20. These guide plates and tractors are adjustable crosswise of the typewriter to enable different widths of continuous stationery to be accommodated.

The electric circuit (FIG. 7) includes an alternating current supply connected through a fused switch to three transformers 24a, 24b, 24c through voltage tappings collectively designated 24. The transformer 24b supplies the desired voltage to the light bulb 15.

The transformer 24c supplies low voltage alternating current more particularly for the transistor element t while the transformer 24a is connected to a rectifier circuit 25 for supplying full wave rectified direct current to the operating relays.

A pair of carriage return contacts 26 are connected in the circuit to the rotary solenoid j for actuation in any suitable manner, preferably upon each return of the carriage. By this means every time a carriage return is made, the rotary solenoid j is energised to feed the continuous stationery one line.

A circuit is made from the negative side of the rectifier circuit 25 to the contacts 26 through the rotary solenoid back to the positive side of the rectifier circuit.

10 A pair of contacts 28 which form part of a manual control switch located adjacent the typewriter key board is connected in series with a Relay R₁ between the positive and negative sides of the rectifier circuit 25. The Relay R₁ has three pairs of normally open contacts. The second pair R₁₂ is connected up in series with the transistor photo-electric sensing element t and with the coil of a second Relay R₂. This circuit is connected across the rectifier circuit associated with the output of the transformer 24c.

15 The transistor element is connected up to the Relay R₂ in a low current circuit. Energisation of the Relay R₂ closes contacts R₁₃ to complete a higher current circuit to the Relay R₁ which supplies the higher current to the rotary solenoid j.

20 The first contacts R₂₁ of the Relay R₂ are connected as a hold on circuit for the Relay R₁ and through the first set of contacts R₁₁ of the Relay R₁ and back to the negative side of the rectifier circuit. A third circuit is made through the third set of contacts R₁₃ of Relay R₁ to the rotary solenoid j. Thus on operation of the switch 28 the Relay R₁ will operate and remain energised and thereby permit supply of current to the rotary solenoid j until the photo-electric sensing means t is energised which will operate the Relay R₂ to break the contacts R₂₁ to the Relay R₁ and hence the circuit to the rotary solenoid is broken to halt feeding of the continuous stationery.

25 In operation and assuming a continuous stationery web is in position on a typewriter with tractor feed pins g engaging the feed perforations at the edges of the web and the endless band 13 is in position on the pins x so as to feed in synchronism with the continuous stationery 30, the stationery is line spaced by the operation of the carriage return mechanism on the typewriter.

30 At the top of one form length, for example, at the first line of data 32, the address of the addressee is typed and the manual control switch contacts 28 are then operated which energise the rotary feed solenoid to feed the continuous stationery and the endless apertured band in synchronism. The feeding continues until at position 33 on the continuous stationery and corresponding position 16b on the endless band which is the second typing position, an aperture in the endless band appears between the light source and the photo-electric sensing means t so that the sensing means are energised. This causes operation of Relay R₂ which opens the contacts R₂₁ to the hold on circuit to the Relay R₁. This opens contacts R₁₃ and breaks the circuit to the rotary solenoid j. The rotary solenoid then ceases to operate. The stationery web 30 (and the endless band) is thereby arrested at this second typing position whereat further data, for example, the date is typed. This operation is repeated for as many times as required, to feed the forms the required distance from one data typing position to the next. When this is typed the manual control switch is again operated to throw the stationery web until the photo-electric means t is again energised at the first information printing position, which corresponds to position 34 on the continuous stationery and position 16c on the endless band.

35 The continuous stationery is thereby halted at the information printing position in the body of the form length and the information is typed in the usual way and as the carriage is fed each line the switch 28 is closed causing the rotary solenoid j to be operated once to feed the continuous stationery one line. When the information has been typed the manual control switch 28 is again operated

to throw the stationery web to the first typing position 32 on the next succeeding form length.

By using apparatus in accordance with the invention we are thereby able to provide an improved apparatus capable of controlling the feeding of continuous stationery and which can be mounted on a typewriter carriage.

What I claim is:

1. Apparatus for feeding continuous stationery around the platen of a printing mechanism, comprising: pin feed mechanism for feeding the continuous stationery, an endless belt, means for feeding said endless belt in synchronism with the continuous stationery and through one complete circuit each time a predetermined length of the continuous stationery is fed, the said endless belt having indicia to correspond to predetermined positions on the continuous stationery, electric rotary solenoid means movable through an accurately predetermined range of actuating movement during each energization and spring retracted to a predetermined starting point upon de-energization, manually controllable switch means for effecting energization of said electric rotary solenoid means, in said range of actuating movement corresponding to a single increment of feeding movement of the stationery, said feeding means comprising a unidirectional driving coupling between said electric rotary solenoid means and the pin feed mechanism for operating said pin feed mechanism to feed the continuous stationery one increment each time the electric rotary solenoid means is energized, said coupling being inoperative on retraction movement of said electric rotary solenoid means, a switch in

circuit with said electric rotary solenoid means, means carried by the electric rotary solenoid means for engaging and opening said switch at the conclusion of each actuating movement of said electric rotary solenoid means for de-energizing said electric rotary solenoid means, carriage control contacts in circuit with said electric rotary solenoid means for controlling the energizing of said electric rotary solenoid means, said manually controllable switch means being in circuit with the electric solenoid means independently of the said carriage control contacts and operable when closed to nullify the controlling action of said carriage control contacts, sensing means cooperating with said endless belt and actuated by the indicia thereon, and relay means controlled by said sensing means and operative in response to actuation of said sensing means for disrupting the circuit between said electric rotary solenoid means and said manually controllable switch means.

20 2. Apparatus as defined in claim 1 in which said sensing means comprises a photo transistor.
